BOTTLE DISPENSING APPARATUS

Walter L. Cunningham, Muncie, Ind.

Application December 26, 1939, Serial No. 310,915

2 Claims. (Cl. 312—88)

My invention relates to improvements in a container dispensing apparatus, particularly of that type wherein the operator may optionally select any one of a number of containers to be dispensed and having coin-controlled means for controlling the dispensing operation.

One of the objects of my invention is to provide a dispenser having a plurality of communicating slots in the top portion thereof through which the necks of the containers are adapted to project, these slots, however, being narrow enough to prevent the removal of a container, with coin-controlled means for controlling the removal of the containers from the apparatus.

Another object of my invention is to provide a structure as above described, wherein practically all of the coin-controlled means and its operating parts may be mounted on the exterior of the casing so that it will not be subject to the corroding moisture on the interior of the casing.

Another object of my invention is to provide a structure having the above characteristic which is extremely simple both in construction and operation.

For the purpose of disclosing my invention, I have illustrated an embodiment thereof in the accompanying drawing, in which—

Fig. 1 is a plan view of a dispenser embodying my invention; and

Fig. 2 is a sectional view on the line 2—2 of Fig. 1.

In the structure illustrated, a suitable skeleton frame is provided, comprising the bottom member 1 and the top member 2. This top member is provided with a plurality of relatively narrow slots 3 terminating in a common slot 4. One of these slots 3 also at one end terminates in an enlarged opening 5. These slots are sufficiently large to accommodate the neck of a container but are sufficiently small to prevent the container from being withdrawn through the slots. The enlarged opening 5, however, is sufficiently large to accommodate the container and permit the same to be withdrawn therefrom.

Upwardly and downwardly extending fins 6 and 7 are arranged within the skeleton frame and so disposed relatively to the slots 3 and 4 as to provide bottle or container channels. Immediately beneath the opening 5, I provide a receptacle 8 having one side open and this open side faces the slot 3 with which the enlarged opening 5 cooperates so that when a container is moved to a position to be removed from the structure, it will have been moved into this re-

ceptacle 8 with its neck projecting through the opening 5.

The opening 5 is partially closed by a hinged blocker 9 secured on the top of the top member 2 by hinge 10. It will be noted that when the hinged blocker 9 is in its normal position, the enlarged opening 5 is sufficiently closed to prevent the removal of the bottle therethrough while at the same time it permits the neck of a bottle to project above the top to permit handling of the bottle.

A closure or blocker member 11 is secured on an oscillating shaft 12 mounted in depending bearings 13 extending downwardly from the top member 2. This closure or blocker member, when in normal position, that is, when the blocker member 9 is in its normal or closed position, is swung into a position to permit free access to the receptacle 8. When, however, the blocker member 9 is swung upwardly to permit the removal of a container through the opening 5, the blocker or closure member 11 is swung across the open face of the receptacle 8, thereby preventing the movement into the receptacle of a container.

The shaft 12 is oscillated by a lever 14 which projects upwardly through the top 2 and is provided with a slot 14' to receive a pin 15' on a vertically disposed plate 15 carried by a shoe 16 which, in turn, is connected to the reciprocating arm 17 of a suitable coin-control device 18. The coin-control device is such that when the arm 17 is moved to its retracted position, the plunger 19 thereof is in a position to receive a coin. In this position, it is to be noted that while the blocker 9 is released so that it can be raised, the blocker member 11 is thrown forward to prevent access to the receptacle 8. In operation, with the parts in the position illustrated and a bottle being in the receptacle 8, the operator, by retracting the plunger 19 to the right (looking at Fig. 2) will retract the shoe or plate 16 to the point where it will permit the raising of the blocker 9 and the removal of the bottle. This retracting movement, at the same time, swings the blocker 11 into the dotted line position and across the face of the receptacle opening preventing the movement of another bottle into the receptacle. Thus a single bottle only may be removed. With the retraction of the plunger 19, the coin releases the connection between the plunger 19 from the arm 17 and escapes into the coin receptacle of the coin controller 18. In order, now, to remove another bottle, a coin is deposited in the coin controller,

thus connecting the plunger 19 with the arm 17. The operator may now push the plunger 19 and with it the arm 17 to the left, looking at Fig. 2, which swings the blocker 11 into its full line position, as shown in Fig. 2. This movement, however, slides the shoe 16 over the blocker 9 and while a bottle may be moved into the receptacle 8, it cannot be axially removed through the opening 5. However, as soon as the operator retracts the plunger 19 to the right, the blocker 9 will be freed, with the blocker 11 again swung into position to prevent the movement of another bottle into the receptacle 8. At the same time the coin releases the plunger 19 from the arm 17 and to remove another bottle, another coin will have to be deposited.

I claim as my invention:

1. A coin-controlled dispenser for containers comprising a slotted top member having a plurality of inter-communicating slots of such dimension as to permit the neck of a container to project therethrough while restricting passage of the body of the container, one of said slots being enlarged to provide a passage opening to permit the passage of a container therethrough, a receptacle disposed beneath said enlarged opening having one side open to permit the movement of a container into said receptacle, a blocker member oscillatingly supported from the under face of said top member and normally in position to permit a container to be deposited in said receptacle, a second blocker member at least partially covering said enlarged opening and swingable to permit the removal of a container through said opening, a coin-controlled means for operating said first-mentioned blocker member, and stop means controlled by said coin-controlled means for preventing the opening of

said second-mentioned blocker member when the first-mentioned blocker member is in a position to permit a container to be moved into said receptacle, the construction being such that said stop means releases said second-mentioned blocking means when the first-mentioned blocking means is moved to block the entrance of said receptacle.

2. A coin-controlled dispenser for containers, comprising a slotted cover member having a plurality of inter-communicating slots of such dimensions as to permit the neck of the container to project therethrough while restricting the passage of the body of the container, one of said slots being enlarged to provide a passage opening large enough to accommodate the body of a container, a receptacle arranged beneath said enlarged opening having one side open to receive a container therein, a blocker member for said enlarged opening at least closing the opening sufficiently to prevent the removal of the container through said opening and swingable to unblock said opening, a blocker member hinged beneath said cover and swingable in front of the entry to said receptacle, a lever connected to said second-mentioned blocker member and projecting through said cover, a coin-controlled reciprocating plunger for operating said lever, a stop carried by said plunger and movable into obstruction position to said first-mentioned blocker member when the plunger is moved to swing the second-mentioned blocker member into unblocking position and removable from obstructing position when said plunger is moved to swing said second-mentioned blocker member into blocking position.

WALTER L. CUNNINGHAM.
